UNITED STATES PATENT OFFICE.

GEORGE W. THOMPSON, OF NEW YORK, N. Y.

DESIGN FOR A CABINET.

SPECIFICATION forming part of Design No. 31,695, dated October 17, 1899.

Application filed March 17, 1899. Serial No. 709,550. Term of patent 7 years.

To all whom it may concern:

Be it known that I, GEORGE W. THOMPSON, a citizen of the United States, and a resident of New York, in the county of New York and State of New York, have invented and produced a new and original Design for a Business-Cabinet, of which the following is a specification.

My design consists in a new shape and configuration of a structure for a business-cabinet; and the essential features of my design consist of a base, two end columns rising from the base, a cornice surmounting the columns, two vertical series of squares adjacent to the columns, respectively, a horizontal series of squares adjacent to the cornice, and two vertical series of oblongs intermediate of the assemblage of the squares.

My design is illustrated in the accompanying drawing, in which the letter A indicates the base; B, the end columns; C, the cornice; D D D', the vertical and horizontal series of squares, and F F the vertical series of oblongs. The oblongs F F are divided from each other and from the squares D D D', as by rectilinear strips e.

Having described my invention, what I claim as new, and desire to secure by Letters Patent, is—

The design for a cabinet, as herein shown and described.

GEORGE W. THOMPSON.
